CONTROL APPARATUS FOR RADIO RECEIVING INSTRUMENTS

Filed Oct. 1, 1930

UNITED STATES PATENT OFFICE

JAY E. WHITE, OF DETROIT, MICHIGAN, ASSIGNOR TO CHRYSLER CORPORATION, OF DETROIT, MICHIGAN, A CORPORATION OF DELAWARE

CONTROL APPARATUS FOR RADIO RECEIVING INSTRUMENTS

Application filed October 1, 1930. Serial No. 485,802.

The main objects of the invention are to provide control apparatus which has its operating members arranged in a compact unit; to provide a compact operating unit for radio control apparatus which is particularly adapted for installation on the instrument board of a vehicle; to provide flexible means for connecting the operating members with the control apparatus; and to provide means 10 of this kind which can be readily conditioned so as to adapt the apparatus for installation in vehicles having instrument boards of various constructions and inclinations and which are located at diversed distances from the receiving set.

An illustrative embodiment of my invention is shown in the accompanying drawing, in which:

Fig. 1 is a fragmentary vertical section of a vehicle body showing a radio receiving set which embodies my improved control apparatus.

Fig. 2 is a fragmentary vertical section of a radio receiving set showing the control apparatus in detail.

Fig. 3 is a transverse vertical section taken on the line 3-3 of Fig. 2.

Fig. 4 is a vertical section taken on the line 4-4 of Fig. 2.

Fig. 5 is a side elevation of an operating unit for a radio control apparatus which embodies a modified form of the invention.

In the form shown in Figs. 1 to 4 inclusive, a radio receiving set including a casing 1 which is supported on a bracket 2, secured to a dash 3 of a vehicle is located directly above the toe board 4 thereof. Mounted in the casing is a rheostat 5 which includes a coiled resistance member 6 and a variable 35 sliding contact 7. The contact 7 is slidably mounted on a support 8 which is located above the resistance member 6. A tuning device, such as a condenser or variometer including a stationary part 9 and a rotatable part 10, is mounted in the casing in spaced 40 relation to the rheostat 5. For the purpose of illustration, these two instruments are shown to be out of alinement, but it is intended that they be understood to be substantially 45 in alinement with each other. The rotatable 50

part 10 of the tuning device has a shaft 11 on which a toothed pulley or sprocket 12 is mounted. Journaled in the casing 1 is a shaft 13 having a toothed pulley or sprocket 14 thereon around which a belt 15 is disposed. 55 The belt 15 has apertures for receiving the teeth of the pulleys 12 and 14 and it also extends around the latter pulley.

Mounted on the instrument board 16 of the vehicle is a disc-shaped support 17 which has a tubular boss 18 extending inwardly through an aperture in the instrument board. A channel-shaped bracket 19 having a downwardly extending side through which spaced apertures 21 and 22 are formed is mounted on the outer periphery of the boss 18 which is threaded internally so as to receive an externally threaded bearing member 23 having an enlarged head 24 by which the bracket 19 is clamped in place. 60

A tubular stem 25 extending through the instrument board 16 is journaled in the bearing member 23 and has a knob 26 on its outer end and a worm 27 on its inner end portion on which a nut 28 is threaded. A flexible 65 cable 29 is secured at one end to the nut 28 and at its other end to a block 30 which is carried by the belt 15. This cable extends through a flexible tube 31 which is secured at its forward extremity in the aperture 22 of the bracket 19 by an attaching member 32. The inner end of the flexible tube 31 is secured 70 between the jaws of a clamp 34 mounted on a support 35 in the casing 1.

Concentrically arranged in the tubular 75 member 25 is an operating element which includes a shiftable stem 36 having a knob 37 on its outer end. The inner end portion of the stem 36 is attached to a flexible cable 38 which extends centrally through the worm 27 80 and through the aperture 21 in the bracket 19. The cable 38 is attached to the sliding contact 7 of the rheostat by a screw 39 and the main portions of this cable are also 85 enclosed within a flexible tubing 40 which is secured at its inner end to the support 8 of the sliding contact by an attaching member 41 and is fastened at its outer end to the downwardly extending side 20 of the bracket 19 by 90 an attaching member 42. 95

A cup-shaped dial 43 is journaled on the periphery of the support 17 and is provided with internal teeth 44 which mesh with the teeth of a pinion 45 that is rigidly mounted 5 on the tubular sleeve 25. The dial 43 has an arcuate groove in which a transparent scale 46 is located. This dial also has an arcuate groove 47 for receiving the stem 25 of the operating unit. Mounted on the bracket 19 is 10 a bulb supporting bracket 48 having a bulb 49 thereon which registers with a slot 50 in the instrument board and with the scale 46.

In operation, the tuning device is regulated by rotating the knob 26 and stem 25 so 15 as to move the nut 28 linearally. This movement of the nut shifts the cable 29 forwardly and rearwardly which in turn actuates the belt 15 turning the rotatable part of the tuning device. The rheostat 5 is regulated by 20 shifting the knob 37 and the stem 36 inwardly and outwardly with respect to the tubular stem 25. In this construction, the operating elements by which the rheostat and tuning device are selectively regulated are combined 25 in a compact unit which may be conveniently mounted on the instrument board of a vehicle. The flexible cables 29 and 38 by which the elements of the operating unit are connected with the control apparatus of the tuning 30 device and rheostat, respectively, may be made of any suitable length so as to conform with the construction of the particular vehicle for which the apparatus is intended. These flexible connecting members allow the compact control unit to be arranged in misalignment 35 relative to the receiving set and they permit regulating apparatus of substantial uniform design to be conveniently installed in vehicles having instrument boards of diverse inclinations.

In the form of my invention shown in Fig. 5 the rheostat regulating mechanism is identical to that shown in Figs. 1 to 4 inclusive. It includes a knob 37' on a stem 36' which is 45 slidably mounted in a rotatable control element 26'. The rotatable element 26' includes a worm 51 which has both advance and return threads 52 and 53, respectively. Threaded on the worm 51 is a nut 28' to which a cable 29' is attached. The cable 29' extends 50 through an aperture in the downwardly extending side 20' of a bracket 19' which is mounted on the instrument board 16', in the manner described above, by a bearing member having a head 24'. This cable operates a belt, not shown, of a tuning device in the manner described above. Rotatably mounted at 55 on the face of the instrument board 16' is a dial 55 having external teeth 56 on its periphery which mesh with a pinion 57 that is rigidly secured to the worm 51. The instrument board 16' has a slot 58 registering with the dial and with a light bulb 49' which is 60 supported on the bracket 19'.

With this form of my invention, the nut 28'

is shifted forwardly and rearwardly by continuous rotation of the knob 26' and worm 51 in a single direction. This action causes the tuning device to be rotated in one direction to the full extent of its capacity and then to be rotated in the other direction. The shiftable operating element regulates the rheostat in the manner described in connection with the Figs. 1 to 4 inclusive.

Although but two specific embodiments of this invention have herein been shown and described, it will be understood that various changes in the size, shape and arrangement of parts may be made without departing from the spirit of my invention and it is not my intention to limit its scope other than by the term of the appended claims.

I claim:

1. In a radio receiving apparatus including a rheostat and a tuning element, control apparatus for regulating said rheostat and tuning element including a pair of concentric operating members, one of said members being rotatably adjustable and the other being slidably adjustable independently of said rotatably adjustable member.
2. In a radio receiving apparatus including a rheostat and a tuning element, control apparatus including a slidably adjustable operating member for regulating said rheostat and a concentric rotatably adjustable operating member operable independently of said slidably adjustable member for regulating said tuning element.
3. In a radio receiving apparatus including a pair of variable instruments, control apparatus for selectively regulating said instruments including a pair of concentric operating members, one of said members being shiftable and the other being rotatable independently of each other.
4. In a radio receiving apparatus including a pair of variable instruments, control apparatus for said instruments including a pair of flexible shiftable members, and a manual operating unit including a shiftable element for actuating one of said flexible members and a concentric rotatable element supporting said shiftable element for actuating the other flexible member.
5. In a radio receiving apparatus including a pair of variable instruments, control apparatus for said instruments including a pair of flexible shiftable members, a manual operating unit including a shiftable element for actuating one of said flexible members and a concentric rotatable element supporting said shiftable element for actuating the other flexible member, and indicating means operable by said rotatable element for disclosing the setting of the instrument which said rotatable member regulates.
6. In a radio receiving apparatus including a pair of variable instruments, control apparatus for said instruments including a

pair of shiftable members, a nut on one of said shiftable members, a rotatable operating element having a worm threaded in said nut for actuating the latter shiftable member, and a second operating element shiftably mounted on said rotatable operating element and attached to the other shiftable member for actuating the same.

7. In a radio receiving apparatus including a pair of variable instruments, control apparatus for said instruments including a pair of shiftable members, a nut on one of said shiftable members, a rotatable operating element, a worm on said rotatable operating element threaded in said nut and having advance and return threads whereby said nut, and the shiftable member upon which it is mounted are shifted in diametrically opposite directions by continuous rotation of said rotatable operating element, and an operating element shiftably mounted on said rotatable operating element and attached to the other shiftable member for actuating the same.

25 8. In a radio receiving apparatus including a variable rheostat and a variable tuning device, control apparatus for said rheostat and tuning device including a pair of flexible shiftable members, one being connected with said rheostat and the other with said tuning device, a rotatable operating element having a worm thereon, a nut threaded on said worm and attached to the shiftable member of said tuning device, and a second operating element shiftably mounted on said rotatable operating element and attached to the shiftable member of said rheostat.

40 9. A radio receiving set including a casing having a pair of variable instruments therein, control apparatus for said instruments located in said casing, a support spaced from said casing, an operating unit mounted on said support including a rotatable manually operable element and a shiftable manually operable element, the latter element being shiftably mounted on said rotatable element, a flexible cable extending into said casing and connected at one end 45 with the control apparatus of one instrument and at its other end with said shiftable operating element, means on the rotatable element for converting rotary movement thereof to lineal movement, and a flexible cable secured at one end to said means and at its other end to the control apparatus of the other instrument.

JAY E. WHITE.
